United States Patent Office.

EDWARD HATCH, OF CHARLESTOWN, MASSACHUSETTS.

Letters Patent No. 74,354, dated February 11, 1868.

IMPROVEMENT IN CLASPS FOR BELTS.

The Schedule referred to in these Letters Patent and making part of the same.

TO ALL PERSONS TO WHOM THESE PRESENTS SHALL COME:

Be it known that I, EDWARD HATCH, of Charlestown, in the county of Middlesex, and State of Massachusetts, have invented a new and useful Clasp for a Lady's Belt, or other article of like character; and I do hereby declare the following to be a full, clear, and exact description thereof, reference being had to the accompanying drawings, making a part thereof. Of the said drawings—

Figure 1 denotes a top view, and

Figure 2 an edge view of the clasp.

Figure 3 is a bottom view of the smaller part of the clasp.

Figure 4 is a longitudinal section, taken through the catches, their spring, and case.

The object of my invention is to produce a clasp, which, when applied to a lady's belt, or other article, will enable such belt or article to be readily either tightened or loosened, as may be desirable, and this without so disconnecting the two parts of the clasp as to render the belt or article to which it is applied liable to fall from the wearer while being adjusted.

My said clasp consists of two parts, A B, the same being made of thin plate metal, of any suitable kind, such as is ordinarily employed for the manufacture of articles of this character. The longer part, A, of the clasp, I make of a rectangular or any other desired shape, and form in the same two parallel slots, $\alpha\alpha'$, running longitudinally thereof. The inner side, e , of each of such slots is straight, and parallel with the side of the part A, the outer side, d , of each of such slots being serrated or formed with a series of teeth, $e e$, &c., the same being shown in fig. 1. The smaller catch part of the clasp, or that marked B, I also construct of a rectangular shape, and on the upper surface thereof, and extending longitudinally of it, I make a cylindrical or other proper-shaped chamber, f , for the reception of two spring-catches, $g g'$, the same having the shape as shown in fig. 4. The said catches consist of two pieces of wire, bent at right angles to each other, the lower half or leg of each being provided with a head or button, h , to act in conjunction with the aforesaid series of teeth e . The said lower portions of the catches project through a slot, i , formed through the lower face of the part B, in manner as shown in fig. 3. The said catches are forced apart by a coiled or helical spring, J , or its equivalent, bent as shown in said figure. The other ends of the catches project from the ends of the said case f , and may be provided with heads or knobs, $k k$, by which each of the said catches may be forced inward, and out of the notches or series of teeth with which they operate. Furthermore, from the under face of the said part B, four studs, $l l l l$, extend downward. These studs are so disposed that when the two parts of the clasp are together, two of the said studs shall be on each side of the middle bar, m , of the part A, and thus serve to maintain the part B, when moved over the portion A, in its proper path of movement. Each of the said parts A and B is to be formed so that it may be readily attached to a belt or band.

In operating with the said clasp, if we suppose the two parts thereof to be attached to a belt, and such belt to be clasped around a lady's waist, or other part of her person, if it is desirable to either tighten or loosen such belt, she has only to press, by means of her thumb and fore-finger, upon the knobs $k k$, and the catches will be forced out of their notches, and the part B may be easily slid in either direction, as circumstances may require.

This invention has been found to be very useful for the purpose for which it is designed.

I claim my improved belt-clasp, composed of the plate A, (formed with the slots $\alpha\alpha'$, and the teeth or serrations $e e$, &c.,) and the plate or part B, (provided with the chamber f , the spring-catches $g g'$, and stud $i i$), the said parts being arranged, constructed, and applied together in manner as set forth, and so as to operate as explained.

EDWARD HATCH.
